Primary Examiner — Anhdao Doan

(21) Appl. No.: **29/758,246**

(74) Attorney, Agent, or Firm — Finnegan, Henderson, Farabow, Garrett & Dunner, L.L.P.

(22) Filed: **Nov. 13, 2020**

(57) **CLAIM**

(51) LOC (13) Cl. **24-01**

The ornamental design for an operation device for an X-ray apparatus, as shown and described.

(52) U.S. Cl.

USPC **D24/158**

DESCRIPTION

(58) **Field of Classification Search**

USPC D24/107, 158-161, 185, 186; D13/168;
D14/218
CPC .. A61B 6/03; A61B 6/035; A61B 5/05; A61B
5/055

See application file for complete search history.

FIG. 1 is a perspective view of an operation device for an X-ray apparatus showing our new design;
FIG. 2 is a front elevational view thereof;
FIG. 3 is a rear elevational view thereof;
FIG. 4 is a right-side elevational view thereof;
FIG. 5 is a left-side elevational view thereof;
FIG. 6 is a top plan view thereof; and,
FIG. 7 is a bottom plan view thereof.
